(57) **CLAIM**

The ornamental design for a receiver configuration for a bottling machine as shown and described.

DESCRIPTION

FIG. 1 is a bottom perspective view of a receiver configuration for a bottling machine in accordance with an embodiment of my new design.

FIG. 2 is a top perspective view thereof.

FIG. 3 is a front elevation view thereof.

FIG. 4 is a left side elevation view thereof.

FIG. 5 is a top view thereof; and,

FIG. 6 is a bottom view thereof.

The rear and right-side elevation views are omitted as they are mirror images of the front and left side elevation views, respectively.

The broken lines in the drawings depict portions of the receiver configuration for a bottling machine which form no part of the claimed design.
